UNITED STATES PATENT OFFICE

2,293,351

SOUND ABSORBING CONSTRUCTION

Richard N. Meginnity, Chicago, Ill., assignor to
The Celotex Corporation, Chicago, Ill., a cor-
poration of Delaware

Application December 16, 1939, Serial No. 309,583

4 Claims.

(Cl. 20—4)

This invention relates to improvements in sound absorbing constructions, particularly those in which the sound absorbing material is concealed behind a diaphragmatic or perforated metal decorative facing.

Acoustical corrective surfaces which have as a decorative surface a diaphragmatic or perforated face are usually fabricated into metal pan units in which are supported sound absorbing units. The diaphragmatic, perforated metal pan or foraminous surfacing unit is used as a facing and a supporting member for sound absorbing material, usually hair felt, mineral wool, composition felted fibre board, balsam wool, porous ceramic bodies, and the like constructions.

These materials are not usually used in their loose, fibrous, or granular condition because they are inconvenient to handle and because the sound absorption characteristics of these materials when in this condition are not uniform. Also, if they are used in this loose condition, the fibres or granules tend to filter through the openings in the foraminous construction into the room below. To overcome these objectionable features, the materials for the absorption units are usually fabricated into preformed units by felting or bonding with a suitable adhesive as is disclosed in the prior art, as for example in the patent to Norris 2,172,771 granted September 12, 1939, and Weiss 2,147,276 granted February 14, 1939.

It has been also found that in order to obtain satisfactory sound absorption characteristics of a foraminous unit and its sound absorption pad that the sound absorption pad should be suitably spaced from the surface of the foraminous sheet forming the metal pan unit. Many forms of supports have been previously used; but, these are generally rather costly to form and install, and they usually are not satisfactory in that openings in the surface of the metal pan unit may thereby become covered causing a non-uniform breathing across the surface of the foraminous unit which results in leaving unsightly dirt streaks and the like on the face of the unit.

It is, therefore, a principal object of the invention to provide a novel sound absorbing unit assembly in which the objectionable features of the prior sound absorption unit assemblies are overcome and to form a sound absorption pad support which is substantially fool-proof in the erection, which may be speedily installed, and which is inexpensive.

A still further object of the invention is to provide a novel sound absorption pad support which is adapted for various lengths of sound absorption pads and furthermore may be adapted either for application longitudinally or transversely of the pad.

Without referring in detail to the construction of the sound absorption pad and support therefor, the invention relates to a body of sound absorbing material which is enclosed in a suitable wrapper, wherein the material of the sound absorption pad is confined by the wrapper against the escape of the fine particles therefrom, while the wrapper is of such a character that the sound absorbing characteristics of the material forming the pad is not appreciably modified by the wrapper or sheath therefor. The wrapper or sheath should, however, be preferably a thin flexible sheet material which may be substantially impervious to the passage of air but is of such a material that it functions as a diaphragm for transferring any of the sound waves impinging thereon to the sound absorption material. In combination with the novel sound absorption pad formed in this manner, it is preferred to use a novel pad support which may be readily affixed to the pad and is adapted to space the sound absorption pad from the metal pan unit or other suitable foraminous surfacing sheet without injuring the wrapper for the sound absorption pad.

Further objects, features, and advantages of the invention will become apparent from the following detailed description of the preferred embodiment and modifications thereof of the invention, as illustrated in the accompanying drawing, wherein like reference characters indicate similar parts:

Figure 1 is a sectional view in elevation illustrating the sound absorption pad assembled in place in a metal pan unit and supported from a face thereof by the novel sound absorption pad support;

Figure 2 is a plane view of a metal pan unit partly broken away and illustrating the manner in which the novel sound absorption pad support is affixed to a sound absorption pad;

Figure 3 is a view illustrating the formed sound absorption pad support in its retracted position; and,

Figure 4 is a modified form of the sound absorption pad support as illustrated in Figure 3.

Referring to Figure 1, the sound absorbing construction comprises a facing 10 which is preferably in the form of a foraminous sheet metal

pan and is supported in spaced relation from the ceiling 11, and between the facing and the ceiling, there are positioned sound absorbing units 12. The perforated metal pans 10 are preferably supported from the ceiling by means of furring strips 13 which are as illustrated substantially T shaped in cross section and are suitably fastened to the wall or ceiling 11 by any suitable securing means, as the screws 14. The furring strips have downwardly extending leg portions 15 and are provided with outwardly formed longitudinal beads 16 adapted to resiliently grip complementally formed beads 17 on the upturned flanges 18 of the metal pans. In erecting the metal pan units in position, the upturned flanges 18 or marginal portions of the metal pan units are inserted between the leg portions 15 of the furring strips with the beaded portions 17 thereof being engaged by the complementally formed portions 16 of the furring strips whereby, as the furring strips resiliently engage the upturned flange portions of the metal pans, the metal pans are rigidly affixed in position and are adapted to be assembled or retracted from their position. The metal pan construction and the supports therefor are only disclosed as being illustrative of a suitable wall surfacing construction adapted for acoustical construction in connection with which the novel sound absorption material and support therefor are to be further described in detail.

Although the sound absorption unit 12 may be supported in direct contact with the interior surface of the perforated facing or metal pan members 10, it is preferred, however, to space the sound absorbing unit 12 a substantial distance from the inner face of the facing member. Referring to Figures 1, 2, and 3, pad supporting members 19 space the sound absorption pad 12 from the inner face of the metal pan units 10. The pad support 19 is originally formed preferably as a tightly coiled spring, as illustrated in Figure 3, having hooked shaped end portions 20 having inturned ends 21 thereof preferably pointed for piercing the sheath or wrapper 22. It is preferred that the hooked shaped end portions 20 shall be transversely positioned with respect to the axis of the coiled pad support 19 so that the lower edge of the coiled member shall be contiguous to the sheath or wrapper 22 of the pad support, as illustrated in Figure 1, although it is to be understood that it is within the scope of this invention that the hooked shaped end portion 20 may have the in-turned ends 21 thereof substantially in alignment with the axis of the coiled pad support.

Although the pad support 19 is preferably a coiled and resiliently formed member, it is obvious that it may be coiled as indicated in its extended position, Figure 1, without making the absorption pad support adapted to have the coils thereof close upon themselves when removed to return to the shape as illustrated in Figure 3. However, for convenience in packaging, it is preferred that the pad support shall be made in the form of a resilient coiled spring which is adapted to be extended, as illustrated in Figure 1, and also adapted to be extended for various length or widths of pads 12 without the necessity of providing various sizes of the sound absorption pad support for different sizes of sound absorption units. It is preferred to form the sound absorption pad supports so that when they are extended from the shape illustrated in Figure 3, which is substantially a full size illustration of the pad support, it will be adapted to fit a sound

absorption pad which is substantially 24" long, the usual size of the sound absorption pads being such that they will fit a metal pan unit substantially 12" x 24" in length.

It is obvious from the construction illustrated in Figures 1 and 2 that three pad supports 19 are sufficient to satisfactorily support the sound absorption pad in position in the metal pan unit. A particular advantage of this form of sound absorption pad support is that these pad supports may be applied as the sound absorption pads are being erected in position or they may be applied to the sound absorption pads 12 and the pads and support therefor mounted within the metal pan to be shipped as a complete unit ready for erection in the wall facing which is adapted for acoustical correction. Although the pad supports 19 have been illustrated as being applied longitudinally with respect to the sound absorption pad 12, as illustrated in Figure 2, it is obvious that these pad supports may be suitably applied transverse with respect to the sound absorption pad without departing from the scope of the invention.

As the prongs 21 readily pierce the wrapper 22 and extend into the sound absorption material forming the pad, it is obvious that the sound absorption supports are firmly affixed in place forming a sound absorption pad which may be considered as having the supports directly affixed thereto or which may be readily separated therefrom or affixed thereto, depending upon whether the pad and support are to be fabricated as a unit or whether they are to be applied as the construction is erected in place.

It is preferred that the wire from which the sound absorption pad support is formed shall be of sufficient gauge to form a substantially stiff support for the pad when the support is in an extended position, as in Figure 1, and that the support when removed from the pad shall, because of the resiliency of the material of which it is formed, return to its original condition as indicated in Figure 3. Although this is the preferred form, it is obvious that a material may be used for forming the pad support and coiled as in Figure 3, which, upon being extended to fit the pad support, will not return to its original shape because the material will not have been heat treated to retain its resiliency and in this instance the material forming the pad support preferably will not be formed of spring steel.

It is preferred to fabricate the coiled wire support 19 so that it will have an outside diameter substantially $\frac{3}{8}$ " to $\frac{1}{2}$ " and a length of approximately $1\frac{1}{4}$ " as coiled, as illustrated in Figure 3, the length of the hooks 20 at each end being additional. The diameter of the coiled wire support when it is extended to a length of substantially 24" becomes substantially $\frac{1}{4}$ ". It is preferred that the prongs 21 shall be pointed a sufficient amount to readily penetrate the wrapper 22. The preferred diameter of the wire from which the material is formed is substantially 0.025", and it is also preferred that the finished coiled wire support 19 shall be galvanized as a safeguard against rusting. Although it is preferred that these coiled pad supports shall be galvanized, it is obvious that any other suitable form of coating which will prevent corrosion is satisfactory and within the scope of this invention.

As previously described, it is preferred in forming the coiled wire supports that the hooks 21 shall lie substantially in the same plane to pre-

ent any warping tendency of the installed support so that at all times the pad support shall directly abut the face of the sound absorption pad to which it is applied without causing warping of the pad away from the support. The tension of the coiled support preferably shall be such that the coiled support, when it is erected in position, will not cause the sound absorption pad to buckle out, the tension being only sufficient to maintain the coiled support in place. When the pad supports are used in conjunction with yielding pads, it is preferred to form the supports from material which after it is formed into the coiled supports may be formed into its extended position by stretching the coiled support substantially the length of the pad which length is sufficient to stress the material forming the support beyond its elastic limit so that its elongated position is retained. However, with a rigid form of absorption pad, the coiled pad support may be formed from material which, after it has been extended for use may return to its original shape.

Figure 4 illustrates a modified form 23 of the coiled sound absorption pad support 19 illustrated in Figure 3. In the modified form illustrated in Figure 4, it is preferred that the ends of the pad support shall be substantially L shaped as at 24. It is preferred to weld to the L shaped ends 24 tacks or nails 25 with the head portion 26 welded to the L shaped end portion 24. A particular advantage of the modified form of construction is that the head 26 reduces the tendency of the coiled spring, if the tension happens to be too great, to tear the wrapper 22 at the point to which the pad support is applied. It is obvious that the modified form 23 of the coiled pad support may be coiled from the same size wire to the same diameter and length of coil as the preferred form, illustrated in Figure 3, and that it may also be suitably coated to prevent corrosion as has been previously described, without departing from the scope of the invention.

The sound absorption unit 12 to which the novel pad support is affixed preferably comprises a body of porous, fibrous, granular, or ceramic material 27 enclosed in the envelope 22 of thin flexible sheet material. The sound absorption unit may also be in the form of a flexible pad of felted fibres such as hair felt, or a semi-rigid tile of wood fibres, mineral, or glass wool, or a rigid tile of porous ceramic substance, or it may be a body of loose fibrous or granular material such as wood fibres, mineral wool, crushed pumice, coke, slag or the like materials.

It is preferred that the wrapper 22 may be folded and arranged as illustrated in Figure 2 with the folded portions joined to the body portions by means of a suitable adhesive to form a unit which is convenient to fabricate and to handle. It is also preferred that the overlapping portions may be adhesively affixed together in such a manner as to seal the sound absorption material 27 within the wrapper 22 so that no loose particles will escape from the wrapper. The prongs 21 or 25 of the modified pad support as they are affixed to the sound absorption pad such as disclosed in Weiss 2,147,276, granted February 14, 1939, may serve to substantially seal the opening formed by the prongs thus preventing any of the material from within the pad from escaping.

Suitable sheet materials which may be used in combination with the novel pad support may be sized or unsized paper, metal foil, such as zinc,

copper, aluminum, and other metals and alloys, asbestos paper and film forming materials such as cellulose, acetates, esters, and ethers. Papers of various kinds and thicknesses may be employed but a thin flexible paper in which the fibres are irregularly arranged is preferred with the paper being substantially 0.0025" in thickness. The metal foil, if used as a wrapper, is preferably substantially 0.003" in thickness.

It is obvious there has been disclosed a novel sound absorbing pad support and a combination thereof with a pad support, and particularly, a sound absorption pad support which is inexpensive to manufacture and which is light in weight; and in connection with which because of its small size, the packaging and shipping costs thereof are reduced to a minimum. Other advantages of the novel pad support are that the supports, when applied to a sound absorption pad, cannot shift their relative position with respect to the sound absorption pad or to a metal pan unit; and, as the pad support is formed from coiled wire having no flat surfaces, there is no tendency of the pad support to blanket any of the perforations of the foraminous metal pan which would reduce the efficiency of the sound absorption unit. Furthermore, breathing through all the perforations of the foraminous unit is substantially uniform so that any air borne dust or dirt is deposited substantially uniformly on the exposed ceiling without leaving any objectionable streaks.

Although the coiled sound absorption pad support has preferably been described as being adapted to be affixed to the sound absorption pad, it is also obvious that it is within the scope of the invention, as an equivalent construction, that the coiled pad support may be welded or otherwise secured to the inner face of the metal pan unit or otherwise suitably incorporated in the assembled construction, as by hooking the support to perforations in the metal pan without departing from the scope of the invention.

It will, of course, be understood that various combinations of the features of the invention, other than the combinations illustrated and described, will be obvious to those skilled in the art and are therefore entirely within the scope of the invention as defined by the appended claims. The same applies to various modifications and minor departures from the specific form of sound absorption pad support per se and combinations with a sound absorption pad or unit of the pad support and foraminous metal pan unit as well as the method of and means for forming the sound absorption pad support, herein illustrated and described, which is used for spacing a sound absorption pad from its contiguous facing unit in which it is supported, and which are particularly used for sound absorption constructions for the correction of the acoustics of auditoriums and the like, and the ventilation thereof.

What is claimed is:

1. In combination with the interior surface of a room, a foraminous member mounted in spaced relation with respect to a portion of the interior surface thereof and a sound absorbing unit positioned between said interior surface and said foraminous member, said sound absorbing unit comprising a body of porous sound absorbing material, a wrapper of sheet material enclosing said body and a plurality of helically formed means spacing the sound absorbing unit from the foraminous member, each of said spaced means comprising a coil spring extending across the face

of said unit and spacing the unit from the foraminous member and means for piercing the opposite edges of the sound absorbing unit, whereby the coil spring means are affixed to the sound absorbing body and said means and body may be utilized as a unit.

2. In combination with the interior surface of a room, a foraminous member mounted in spaced relation with respect to a portion of the interior surface thereof and a sound absorbing unit positioned between said interior surface and said foraminous member, said sound absorbing unit comprising a sheet form pad of porous sound absorbing material, slender wire form material helically shaped and interposed between a face of the foraminous member and contiguous face of a sheet formed pad, the helically shaped member resting on the foraminous member and contacting the surface thereof at pitch points along a line extending axially along the helically shaped member and the pad supported on the helically shaped member along a line of pitch points substantially diametrically opposite but longitudinally displaced with respect to the points of contact with the face of the foraminous member.

3. In combination in a sound absorbing assembly, a pan form perforated facing portion, a sheet form pad of sound absorbing material carried

therein and spacing means interposed between the sound absorbing pad and foraminous face, the spacing means comprising an elongated, wire form, helically formed member contacting each of the opposed faces of the foraminous face portion of the pan member and the sound absorbing pad at points along the helically shaped member respectively spaced, a distance apart, equal to the pitch thereof.

4. In combination in a sound absorbing assembly a pan form perforated facing portion, a sheet form pad of sound absorbing material carried therein and spacing means interposed between the sound absorbing pad and foraminous face, the spacing means comprising an elongated, wire form, helically shaped member contacting each of the opposed faces of the foraminous face portion of the pan member and the sound absorbing pad at points along the helically shaped member respectively spaced, a distance apart, equal to the pitch thereof, the helically shaped member at the ends thereof provided with piercing means whereby the helically shaped member is affixed to the sound absorbing pad and the helically shaped member and sound absorbing pad may be utilized as a unit assembly.

RICHARD N. MEGINNITY.
